LIQUID DISPENSING CONTAINER

Jasper Gibbons Grinling, London, England, assignor to W. & A. Gilbey Limited, London, England, a British company

Filed May 11, 1959, Ser. No. 55,875

Claims priority, application Great Britain Nov. 26, 1958

Term of patent 7 years

(Cl. D2—3)

FIG. 1

FIG. 3

Fig. 1 is a rear perspective view of a liquid dispensing container embodying my new design, taken from the bottom and one side;

Fig. 2 is a front perspective view thereof showing the top and side opposite that shown in Fig. 1;

Fig. 3 is a side elevational view thereof; and

Fig. 4 is a fragmentary transverse cross-section taken through the top of the container, with the conventional cork portion of the cap member shown in broken lines.

I claim:

The ornamental design for a liquid dispensing container, as shown and described.
